(57) **CLAIM**

The ornamental design for an optical connector assembly jig, as shown and described.

DESCRIPTION

FIG. 1 is a perspective view of an optical connector assembly jig showing the new design;

FIG. 2 is a front view thereof;

FIG. 3 is a rear view thereof;

FIG. 4 is a right side view thereof;

FIG. 5 is a left side view thereof; and,

FIG. 6 is a top view thereof.

The broken line showing of selected elements is for environmental purposes only and forms no part of the claimed design.

1 Claim, 4 Drawing Sheets

FIG. 1

FIG. 2**FIG. 3**

FIG. 4

FIG. 5

FIG. 6
